UNITED STATES PATENT OFFICE.

WILLIAM H. D. FORD, OF NEW YORK, N. Y., ASSIGNOR TO WESTERN ELECTRIC COMPANY,
INCORPORATED, OF NEW YORK, N. Y., A CORPORATION OF NEW YORK.

IMPULSE-TRANSMITTER.

1,286,981.

Specification of Letters Patent. Patented Dec. 10, 1918.

Application filed June 10, 1916. Serial No. 102,873.

To all whom it may concern:

Be it known that I, WILLIAM H. D. FORD, a citizen of the United States, residing at New York, in the county of Bronx and State of New York, have invented certain new and useful Improvements in Impulse-Transmitters, of which the following is a full, clear, concise, and exact description.

This invention relates to impulse transmitters for use in connection with party line or like systems wherein there are a plurality of subscriber or way-stations on the same line, each station being provided with a selector mechanism adapted, in response to impulses sent over the line, to close a signaling circuit at that station, the number of impulses for calling the stations being different for each particular selector.

This invention has for its object the provision of an impulse transmitter which will be compact, sure and quiet in its operation, easily manufactured, and one which can be easily and speedily adjusted to transmit the proper combination of impulses for calling any particular station on the line.

The impulse transmitter to which this invention relates comprises in general a clockwork mechanism in which energy is stored up by the turning of a handle which winds a spring. When the handle is released, the spring revolves a shaft, upon which is mounted a toothed wheel adapted to operate contact springs to make and break a circuit. Two adjustable cam members are provided for covering up certain of the teeth to permit of the transmitting of any desired combination of impulses. There is also provided means independent of the toothed wheel which, in the operation of the transmitter, renders the contact springs operatively independent of the toothed wheel during a portion of the travel thereof.

In the drawings illustrating this invention, Figure 1 is a side elevation of the impulse transmitter; Fig. 2 is a view of the back end of the impulse transmitter; and Fig. 3 is a view of the back end of the impulse transmitter with a portion of the toothed wheel broken away to show the means for rendering the contact springs operatively independent of the toothed wheel during a portion of the travel thereof.

Referring to the drawings, 5 and 6 designate frame plate members secured together by rods 7 and 8. Supported in these frame

plates 5 and 6 are shafts 10 and 11, the shaft 10 constituting a driving and the shaft 11 the driven shafts of the mechanism. Loosely mounted upon the shaft 10 is a gear wheel 14 adapted to be driven by a spiral spring 15 on said shaft. Gear wheel 14 meshes with a pinion 16 on the shaft 11, which pinion is secured to a gear wheel 17, also on the shaft 11, gear wheel 17 being in mesh with a pinion 18 loosely mounted upon the shaft 10 and secured to a gear wheel 19. The gear wheel 19 in turn meshes with a pinion 20, loosely mounted upon the shaft 11 and secured to a gear wheel 21. The gear wheel 21 meshes with a worm on a governor shaft 22, which is arranged at right angles to the shafts 10 and 11, and supported between arms 23, 23 formed integrally with the plate 6. The governor consists of two weighted spring arms 24 and 25, which, as the governor shaft 22 is rotated, are caused to throw the weights outwardly against the inner face of a metal drum 26, the friction of the weights and drum tending to retard the movement of the rotating parts and keep them at a constant speed.

The specific arrangement of parts whereby the circuits are controlled to cause impulses to be sent out on the line is as follows: Mounted upon the inner end of the shaft 11, beyond the frame plate 6, is a wheel or disk 30 having formed on the larger portion of its periphery a plurality of groups of teeth 31, 31 which are adapted to coöperate with spring contacts 32 and 33 to alternately make and break a circuit including these contacts. As shown, the wheel 30 is provided with portions 34, 34 free from teeth, their radii being the same as the radius of the wheel 30 at the base of the teeth 31, 31 in one of which portions the free end of spring 32 is normally positioned out of engagement with the spring 33. The wheel 30 is provided with a portion 37 having a radius equal to that of the outer face of the teeth 31, 31, and which, when passing under the free end of spring 32, maintains contact springs 32 and 33 in engagement to control the duration of the operation of the signaling device at the selected station. As the free end of spring contact 32 rides on top of a tooth, a short impulse of current is sent over the line, and when the spring contact 32 is between two teeth, current is removed from the line for a short

- time. The number of effective teeth in different groups which pass under contact spring 32, is determined by means of adjustable plates or cam members 38 and 39
- 5 pivotally mounted upon the end of shaft 11 in juxtaposition to the toothed wheel 30, each cam member being provided with an arcuated slot 40 concentric with the shaft 11. A screw 41 passing through each slot into
- 10 the face of the toothed wheel, is adapted to secure the cam members 38 and 39 in any adjusted position. The periphery of each cam member preferably has a radius equal to that of the outer faces of the teeth 31, 31.
- 15 The toothed wheel 30 is adapted to make two complete revolutions each time a call is made, and in this connection is provided on one face with a projecting stop lug 50, adapted to engage a movable stop lug 51
- 20 carried by the shaft 10. A cam member 55 is also mounted on the shaft 10 and is adapted to rotate therewith. The cam member 55 is provided with a surface 56 which coöperates with the curved end of the long
- 25 arm of a bell-crank lever 57 pivoted at 58 on the frame plate 6 to move the lever 57 about its pivot point. As the lever 57 is moved about its pivot point, a projection 59 on the short arm thereof engages the contact spring 32 and raises it out of engagement with wheel 30 and into engagement with contact spring 33. In the operation of these particular parts, the shaft 10 is turned by a handle 52 through an angle of about 180
- 30 degrees until the stop lug 51 comes into contact with a stop pin 58 projecting from the frame plate 6. As the handle 52 is turned, the cam member 55 is moved with the shaft 10 and stop lug 51, the end of the long arm
- 35 of lever 57 riding along the surface 56 and surface 65 of the cam member 55. When the handle is released, the two shafts 10 and 11 travel at such a relative speed that the wheel 30 is caused to make two complete
- 40 revolutions while the stop lug 51 is moving back into position to engage stop pin 58 on said wheel. As the shaft 10 revolves under action of the spring 15, the wheel 30 is revolved in the direction of the arrow and
- 45 the teeth 31, 31 thereof engage the free end of contact spring 32 to cause the intermittent engagement of contact springs 32 and 33. When the wheel 30, in its first revolution, has brought the surface 37 thereof
- 50 under the free end of contact spring 32 the surface 56 of cam member 55 engages the end of the long arm of lever 57 and moves the lever 57 about its pivot point to cause the projection 59 to raise and maintain the
- 55 contact spring 32 out of engagement with wheel 30, and the contact springs 32 and 33 in engagement for a complete revolution of wheel 30. The surface 56 of cam member 55 now disengages the end of the long arm of
- 60 the lever 57, permitting the bell-crank lever
- 65 to move in the opposite direction about its pivot under the action of contact spring 32, whereupon the free end of contact spring 32 again engages the surface 37 of the wheel 30. The shaft 10 projects through a mounting plate 54, so that the handle 52 thereon may be easily manipulated from the front of the transmitter.
- 70 The contact springs 32 and 33 are mounted upon a supporting lug 60 formed integrally with the frame plate 6, one of said contact springs being electrically connected with said frame through the toothed wheel 30 or through the projection 59 on lever 57, and the other of said springs being electrically connected with a lug 61 insulated from the frame. The plate 54 and transmitter structure supported thereby is adapted to be mounted in a suitable casing or box with the frame thereof in contact with one circuit terminal, while the lug 61 is adapted to engage a separate circuit terminal.

- What is claimed is:
1. In an impulse transmitter, a driving shaft, a driven shaft, a rotatable toothed wheel, carried by said driven shaft, normally disengaged contact springs brought into and out of engagement by the teeth of said wheel, and a lever controlled by said driving shaft for rendering said contact springs operatively independent of said toothed wheel during a portion of the travel of said wheel.
  2. In an impulse transmitter, a driving shaft, a driven shaft, a rotatable toothed wheel, carried by said driven shaft, normally disengaged contact springs brought into and out of engagement by the teeth of said wheel, and means controlled by said driving shaft for moving said contact springs out of operative relation to said toothed wheel during a portion of the travel of said wheel.
  3. In an impulse transmitter, a driving shaft, a driven shaft, a rotatable toothed wheel carried by said driven shaft, normally disengaged contact springs brought into and out of engagement by the teeth of said wheel, a cam member carried by said driving shaft, and a bell crank lever operated by said cam member for moving said contact springs out of operative relation to said toothed wheel during a portion of the travel of said toothed wheel.
  4. In an impulse transmitter, a driving shaft, a driven shaft, a rotatable toothed wheel carried by said driven shaft, normally disengaged contact springs brought into and out of engagement by the teeth of said wheel, a cam member carried by said driving shaft, and a bell crank lever operated by said cam member to cause the engagement of said contact springs independent of the toothed wheel during the travel of said wheel.

5. In an impulse transmitter, a driving shaft, a driven shaft, a rotatable toothed wheel carried by said driven shaft, normally disengaged contact springs brought into and out of engagement by the teeth of said wheel, a cam member carried by said driving shaft, and a lever operated by said cam member to move said contact springs out of operative relation to said toothed wheel and to maintain said contact springs 10 in engagement during a portion of the travel of said toothed wheel.

In witness whereof, I hereunto subscribe my name this 8th day of June A. D., 1916.

WILLIAM H. D. FORD.
